UNITED STATES PATENT OFFICE.

WATSON R. SMITH, OF JACKSON, MICHIGAN, ASSIGNOR TO VENTILATED CUSHION & SPRING COMPANY, OF CHICAGO, ILLINOIS.

SPRING STRUCTURE.

No. 891,878.

Specification of Letters Patent.

Patented June 30, 1903.

Application filed May 2, 1907, Serial No. 371,528. Renewed May 18, 1908. Serial No. 433,594.

To all whom it may concern:

Be it known that I, WATSON R. SMITH, a citizen of the United States of America, and a resident of Jackson, county of Jackson, State of Michigan, have invented certain new and useful Improvements in Spring Structures, of which the following is a specification.

The main objects of this invention are to provide an improved spring structure particularly adapted to cushions for carriage seats, and also suitable for upholstered furniture and mattresses; to provide an improved arrangement of the various parts of a cushion spring structure; to provide an improved arrangement of springs adapted to offer a certain yielding resistance to compression under normal conditions and to offer increased resistance at times when the weight of the occupant is suddenly and violently shifted on account of the passage of the carriage over sudden rises or depressions in the road bed; and to provide an improved yielding structure for the top frame of a cushion spring. These objects are accomplished by the device shown in the accompanying drawings, in which:

Figure 1 is a top plan of a cushion spring constructed according to this invention, some of the parts of the springs which would be seen below being partly broken away or omitted for the sake of clearness of the illustration; Fig. 2 is a section on the line 2—2 of Fig. 1; Fig. 3 is a detail partly broken away of the bottom frame of the structure, the parts above being broken away; Fig. 4 is a similar plan of the intermediate frame; Fig. 5 is a detail of the metal clip which connects the bases of the springs which form the parts of the intermediate frame shown in Fig. 4; Fig. 6 is a detail of one of the joints of the bottom frame; and Fig. 7 is a detail of another joint thereof.

In the construction shown in the drawings, the structure comprises a top frame 5 and a bottom frame 6 separated by a plurality of helicoidal spiral springs 7 and an intermediate frame suspended from the upper frame by means of a plurality of helicoidal spiral springs 8. The springs 7 and 8 are arranged in pairs each spring 8 being disposed concentrically around one of the springs 7 and having convolutions of larger diameter than the adjacent convolutions of said spring 7. The bottom frame 6 is formed by connecting the bottom convolutions of the springs 7 by

means of a border wire 9, parallel stay-wires 10 and suitable metal clips securing said parts together.

The stay-wires 10 are preferably connected to the spring 7 by means of sheet metal cross-bars 11 split at each end into three tongues 12 and 13. The tongues are wrapped around the stay-wire 10 and the adjacent part of the spring 7, as illustrated in Fig. 7. The bars 14 are similar to the bars 65 11 at their inner ends and are formed as illustrated in Fig. 6 at their outer ends. This is done so that the bottom frame 6 will be of the same size as the top frame for the sake of symmetry in the appearance of the cushion. 70 The outer end of the bar 14 is connected with the spring 7 by a separate tongue 15. Metal clips 16 connect with the border wire 9 such of the springs 7 which are adjacent to it and not connected thereto by their cross-bars. 75

The intermediate frame 17 is formed by twisting the end of the lower convolution of each spring 8 about itself so as to form a substantially circular base part for the spring and then connecting the lower base of each 80 spring 8 with those of the adjacent springs 8 and with a border wire 18 by means of clips 19. These clips are preferably in the form shown in Fig. 5 and they serve as links connecting the component parts of the intermediate frame 17 so that said parts may be capable of yielding slightly to conform with the distribution of weight upon the cushion. This connection is, however, sufficient to cause all of the springs to assist each other 90 in supporting the load upon the cushion.

The upper end of each of the springs 8 is twisted about itself so that the upper convolution forms a complete substantially circular ring. The sheet metal bars 20 extending across the top of each pair of springs, connect the springs of such pair to each other and also connect the top of each pair of springs with the upper convolution of the spring 8 of the adjacent pair. The bars or 100 cross-pieces 20 of adjacent pairs of springs are disposed substantially at right angles to each other, as shown in Fig. 1, so that each pair of springs may yield somewhat with respect to adjacent pairs. The top convolution of each spring 7 is riveted at 21 to the middle of its bar 20. The ends of the bars 20 are split into three longitudinal tongues as in the case of the bars 11 and said tongues are wrapped around the bars which they con- 110

nect in a somewhat similar manner. In the bottom frame it is preferred that the stay-wires 10 lie in the same vertical plane with the adjacent parts of the base convolutions of the springs 7 while in the top frame the connected parts lie in the same horizontal plane with each other. The border wire 22 of the top frame is connected to the adjacent springs by means of clips 23 at such points where the cross-bars 20 of the adjacent springs do not themselves serve this purpose.

In operation the bottom frame rests upon a suitable support, such as, a carriage or seat. The weight of the occupant under normal conditions is supported by the springs 7, said springs being of such strength as to yield readily through the shifting of the weight of the occupant or through slight jolting of the vehicle. In case of severe jolts, the intermediate frame 17 comes into contact with the base frame 6 and the combined power of the springs 7 and 8 is exerted to resist compression.

25 What I claim as my invention and desire to secure by Letters Patent, is:

1. In a spring cushion, the combination of a top frame, a bottom frame, a plurality of spiral springs yieldingly connecting said top and bottom frames, a second set of spiral springs of less height than those of the first set, each located substantially concentric with one of the springs of the first set and being of larger diameter so as to be normally free from the adjacent convolutions of the corresponding spring of the first set, one end of each of the springs in said second set being connected to one of said frames, and an intermediate frame 40 supported by the other end of said second set of springs, said springs and frames being so disposed as to permit the top to be depressed a considerable distance without resistance by said second set and to cause 45 such resistance when the top is further depressed.

2. A spring cushion comprising a bottom frame, a top frame, a set of spiral springs extending between said frames, a second set of 50 spiral springs of larger diameter than those of the first set and of less height, each of said second set of springs being located concen-

trically around the outside of one of the springs in the first set and having one end secured to one of said frames, the inner ends of 55 the different springs of said second set being so secured together as to permit their movement relatively of other springs of said second set.

3. A spring cushion comprising a bottom 60 frame, a top frame, a set of spiral springs extending between said frames, a second set of spiral springs of larger diameter than those of the first set and of less height, each of said second set of springs being located concentrically around the outside of one of the 65 springs in the first set and having one end secured to one of said frames, and metal clips connecting together the adjacent parts of the inner end convolutions of said second set of 70 springs, and forming therewith a flexible frame movable relatively of said top and bottom frames.

4. A spring cushion comprising a bottom frame, a top frame, a set of spiral springs extending between said frames, a second set of spiral springs of larger diameter than those of the first set and of less height, each of said second set of springs being located concentrically around the outside of one of the 80 springs in the first set and having one end secured to one of said frames, the inner ends of said second set being connected together by a floating frame having movement toward and from each of the other frames.

85 5. A spring cushion, comprising a top frame, a bottom frame, a set of spiral springs extending between said frames, a second set of spiral springs disposed, respectively, around and clear of the upper parts of the 90 springs of said first set, and having their upper ends secured to said top frame, and clips connecting the lower ends of the springs of the second set with corresponding parts of adjacent springs of the same set, said second 95 set of springs being of less height than said first set.

Signed at Jackson, Michigan, this 23 day of April 1907.

WATSON R. SMITH.
